DISPENSING CAP

James C. Boyle, Cincinnati, Ohio

Application February 1, 1936, Serial No. 61,975

12 Claims. (Cl. 221—116)

My invention relates to dispensing caps to be placed on containers filled with coffee or other relatively fine ground material, and which dispenses the material from the container in a definite measured quantity.

It is an object of my invention to provide a dispensing cap together with a collar or a series of collars therefor, which may be placed over the ordinary can-type container, and ordinary screw top Mason jar, or which may be placed over the neck opening of a paper sack.

It is a further object of my invention to provide a dispensing cap which insures the dispensing of the correct measured amount of material at each action of dispensing.

It is a further object of my invention to provide a dispensing cap which is so constructed that jamming due to the material being dispensed getting into the dispensing mechanism is avoided, and which provides a simple and easy method of dispensing material without the use of a great amount of effort.

It is a further object of my invention to provide a dispensing cap which when fitted on a container completely seals the same when it is not in use, and prevents dirt or moisture from penetrating the container and which insures the aroma and condition of the material from being impaired.

Another object of my invention is to provide a dispensing cap which as has been heretofore stated may be placed upon a plurality of containers of different kinds, but which may be manufactured extremely cheaply and which gives a very pleasing appearance to the container on which it is placed.

These and other objects of my invention which will be set forth hereinafter or will be apparent to one skilled in the art upon reading these specifications, I accomplish by that certain construction and arrangement of parts of which I shall now describe a preferred embodiment.

Reference is now made to the drawing which forms a part hereof, and in which:

Figure 1 is a plan view with a portion cut away of my novel dispenser.

Fig. 2 is a section of my dispenser shown in Fig. 1, taken on the section line 2—2.

Fig. 3 is a cross section of a modified form of my novel dispenser.

Fig. 4 is a side view of the dispenser shown in Fig. 2 applied to a paper bag or sack, with a portion cut away to more clearly show the construction.

Fig. 5 is a side view of a modified form of

collar used with my dispenser, together with a cage for use with a paper bag.

Briefly, in the practice of my invention, I provide a circular casing 1, with an annular opening 2, and a restricted exhaust opening 3. I do not intend to limit myself to the size and shape of the exhaust opening and merely illustrate a preferred embodiment thereof for the purpose of assisting and understanding my invention. Positioned within the casing 1, is a spider 4, composed of a plurality of radial walls coming together at the center and fastened to the inner side of the casing 1, in order to form a plurality of V-shaped compartments. I provide a circular plate 5 covering the upper openings of the spider compartments 6 which preferably has an annular bead 7 on its edge. This plate 5 is rotatable within the dispenser casing 1.

A second circular plate 8 preferably having a bead on its circumferential edge covers the lower openings of the spider compartments 6. The formation of the spider walls 4 is such that the volume of each compartment as determined by the walls and the upper plate 5 and lower plate 8 is a given, carefully measured amount. It is of course apparent that this volume may be changed by either widening or narrowing the walls 4 or by enlarging the distance between the walls in their radial positions. The walls 4 are fastened to the casing 1 by welding or any other means well known in the art, or it may be preferable to hold them in place by merely the frictional engagement with the slide walls 4, and their other ends are welded or fastened to a central hub 9.

A square shaft 10 projects through the hub 9 outwardly to the plane of the exhaust opening 3. The upper and lower plates 5 and 8 have square apertures in their center through which the square shaft 10 runs in a slidable but non-rotatable relation. I have preferably placed springs 11 against the plates 5 and 8 and abut them against collars 12 which are positioned around the shaft 10 in a non-slidable manner by splitting them and inserting them in grooves 12a in the shaft 10. From this description it is apparent that the springs urge the plates 5 and 8 against the spider edges and at the same time hold the shaft 10 in the position within the dispenser casing 1 itself.

Within the plates 5 and 8 I place apertures 13 of a configuration similar to a cross section of the compartments 6. The apertures in the plate 8 are in staggered relation to those in the plate 5. In the preferred embodiment illustrated in Fig. 50

1. I have shown two apertures 13 and 13a in the upper plate 5 and on opposite sides of the plate. In the lower plate 8, I have shown two apertures 13b and 13c on opposite sides of the plate and at right angles to the opposing apertures in plate 5. In the embodiment shown in Fig. 1 there are eight compartments 6, and by placing the apertures in the plates as above indicated, the operation of the dispenser is as follows: The material in the container when it is inverted will fill the two compartments 6 under the apertures 13 and 13a in the upper plate 5. The lower plate 8 will form a bottom for these two apertures. If the shaft 10 is now turned counterclockwise so the apertures will all move one compartment in that direction, there will be no dispensing as yet, but the two compartments to the left, in counterclockwise direction, will be filled through the apertures 13 and 13a. If now the shaft 10 is again revolved in a counterclockwise direction, the apertures in the plate 8 will position themselves under the first two compartments filled, and will discharge them through the exhaust opening 3. The solid portion of the plate 5 will cover the compartments being discharged so that no more than the measured quantity of material may run through them. It is quite apparent that on each further movement of the shaft 10 in a counterclockwise direction, the apertures will progressively position themselves under following compartments and will successively discharge each compartment while at the same time filling at least two compartments which are not being discharged. I wish to particularly call attention to the fact that my dispenser cap at no time between the registering of any of the apertures with the compartments opens a passageway from the container straight through to the exhaust opening 3.

To facilitate the operation of my dispenser cap I provide a handle 15 keyed to the end of the shaft 10 and preferably urged against the edge 3a of the exhaust opening 3. I cut teeth 16 in the edge 3a of the exhaust opening 3 with sloping shoulders 16a on one side and a sharp shoulder 16b on the other side. This insures that the handle 15 will be revolved at all times in the same direction. It is of course apparent that either direction will be satisfactory but that the handle and thus the shaft 10 to progressively discharge must be always turned in the same direction.

The modification shown in Fig. 3 comprises a circular casing 21 and the spider walls 4 tapered to the hub as is clearly shown in the drawing. In this modification the upper plate 5 is similar to that described above but the lower plate 22 is conical in shape so as to contact the tapered edges of the spider 4. In this instance I have found that a coil spring 23 is more satisfactory than a leaf spring in urging the plate 22 against the wall edges. The aperture openings in both the plates 5 and 22 are similar to that described above.

I provide a cap 25 which fits over the exhaust port edge 3a when the dispenser is not in operation. This cap has a hinged portion 26 through which a circular wire 27 runs and which preferably is positioned in a groove 28 in the container casing itself. I provide a slot 29 in the lip 30 of my cover 25 to permit the handle end 15a to project. From the above it is apparent that the cap 25 may be turned in relation to the container casing, so that the slot 29 may be so positioned as to fit over the crank end 15a at any position on the discharge port 3. In some cases it may be preferable to provide the cap 25 with a spring so

that it will snap into fully open position, or will snap into fully closed position. It may be advantageous to provide a removable cap, but I do not intend to limit myself to any special form of cap.

I provide a series of collars for attaching my dispensing cap to different forms of containers. All of the collars have an annular lip 36 which fits into the annular opening 2 of the dispenser cap. The other end of the collar may have an annular flange 31, Fig. 2, for fitting over the ordinary coffee container 33. Fig. 3 illustrates my collar with a screw flange 34 for fitting over and screwing on the typical opening of a Mason jar 35.

Fig. 4 illustrates a special collar for use with a paper sack. This comprises the collar itself with a flange 36 of a circumference similar to the circumference of the paper sack and over which the paper sack mouth may be placed. There is preferably a bead 36a on the edge of the flange 36 and a spring hoop or collar 37 with split ends 38 formed of resilient material which may be positioned over the paper bag mouth 39 to hold it tightly against the flange 36. Fastened on the inside of my collar is a wire framework 40 which may be worked down through the material in the bag in order to keep the bag in an extended condition.

Fig. 5 illustrates a modification of the bag holder of Fig. 4, the only difference being that the wire cage 40 is attached to the resilient hoop 37 and positions itself on the outside of the bag instead of on the inside. This permits the bag to be set in an upright position no matter how deflated.

While the modifications in Figs. 4 and 5 show collars having a frame for use with bags, it is also apparent that the type of frame I use is not a limitation of my invention but merely for the purpose of illustration since it is apparent that a cylinder of paper, metal or some relatively stiff material may be used in place of the frame illustrated in Figs. 4 and 5.

It is of course to be understood that numerous different forms of my preferred form as described above, may be made without departing from the spirit of my invention.

Having thus described my invention, what I claim as new and desire to secure by Letters Patent, is:—

1. A dispenser cap comprising a plurality of segmental compartments having a given appreciable depth, an upper and lower closure for said compartments comprising plates, said plates being mounted on and movable by a common shaft, two segmental openings in each of said plates on opposite sides thereof, the openings in said lower plate being on a line at right angles to the line of the openings on said upper plate, an arm keyed to said shaft for movement of both the plates, stops coacting with said arm to position said plates so that the openings are all in perfect register with the segmental compartments.

2. A dispenser cap comprising a plurality of segmental compartments having a given appreciable depth, an upper and lower closure for said compartments comprising plates, said plates being mounted on and movable by a common shaft, two segmental openings in each of said plates on opposite sides thereof, the openings in said lower plate being on a line at right angles to the line of the openings on said upper plate, an arm keyed to said shaft for movement of both the plates, stops coacting with said arm to position said plates so that the openings are all in perfect register with the segmental compartments.

register with the segmental compartments, and spring means for urging said plates against said compartment ends.

3. A dispensing cap comprising a circular casing for attachment to the neck of a container, radial walls within said casing defining segmental passages of given depth, a rotatable plate covering each end of said passageways, said plates having apertures of a configuration similar to the passageway ends, the apertures on each plate being staggered in relation to the apertures on the other plate, a shaft for rotating both of said plates together, a handle on said shaft for rotating said shaft, means cooperating with the handle when said apertures are in perfect registry with the passageway openings.

4. A dispensing cap comprising a circular casing for attachment to the neck of a container, radial walls within said casing defining segmental 20 passages of given depth, a rotatable plate covering each end of said passageways, said plates having apertures of a configuration similar to the passageway ends, the apertures on each plate being staggered in relation to the apertures on the other plate, a shaft for rotating both of said plates together, a handle on said shaft for rotating said shaft, means cooperating with the handle when said apertures are in perfect registry with the passageway ends, and springs for urging 25 said plates against the passageway ends.

5. A dispensing cap comprising a casing having a portion to be placed over the neck of a container and a spout portion, a plurality of measured compartments between said portions, 30 said compartments having a top opening and a bottom opening, circular plates covering both of said openings, apertures in said plates, the apertures of one plate being in staggered relation to the apertures in said other plate, a shaft common to both plates for rotating them together, 35 a handle on said shaft and means cooperating with said handle for determining when said plate apertures are in exact registry with a measured compartment, and a cover for said spout portion and having a slot positioned over said handle, said cover being revolvable around the spout but not removable from said casing.

6. A dispensing cap comprising a casing having a portion to be placed over the neck of a 50 container and a spout portion, a plurality of measured compartments between said portions, said compartments having a top opening and a bottom opening, circular plates covering both of said openings, apertures in said plates, the 55 apertures of one plate being in staggered relation to the apertures in said other plate, a shaft common to both plates for rotating them together, a handle on said shaft and means cooperating with said handle for determining when said plate apertures are in exact registry with a measured 60 compartment, said means comprising teeth on said spout portion in which said handle rides.

7. In combination with a dispensing cap for dispensing measured quantities of material a collar one end of which is adapted to fit said cap and the other end of which is provided with an annular flange having a groove, a resilient hoop adapted to be positioned in said groove and a framework projecting outwardly from said flange, 65 so that a paper bag may be placed over the framework with its mouth around said annular flange and in said groove with the hoop surrounding said bag mouth forcing the same in said groove and retaining it in that position.

8. A dispensing cap comprising a circular casing, a shaft positioned axially within said casing, a circular plate slidably, but non-rotatably mounted on said shaft and positioned to rotate within said casing, a frusto-conical plate slidably, but non-rotatably mounted on said shaft at a point adjacent to said circular plate, and adapted to rotate with said shaft and said circular plate, partition walls mounted on said casing and projecting between said plates to form 10 compartments with said plates, apertures in said circular and said frusto-conical plates, the apertures in said frusto-conical plate being in staggered relationship to the apertures in said circular plate, and means for revolving said shaft. 15

9. A dispensing cap comprising a circular casing, a shaft positioned axially within said casing, a circular plate slidably, but non-rotatably mounted on said shaft and positioned to rotate within said casing, a frusto-conical plate slidably, but non-rotatably mounted on said shaft at a point adjacent to said circular plate, and adapted to rotate with said shaft and said circular plate, partition walls mounted on said casing and projecting between said plates to form 20 compartments with said plates, apertures in said circular and said frusto-conical plates, the apertures in said frusto-conical plate being in staggered relationship to the apertures in said circular plate, means for revolving said shaft, and 25 springs urging said plates toward each other.

10. A dispensing cap comprising a circular casing, a shaft positioned axially within said casing, a circular plate slidably, but non-rotatably mounted on said shaft and positioned to rotate 30 within said casing, a frusto-conical plate slidably, but non-rotatably mounted on said shaft at a point adjacent to said circular plate, and adapted to rotate with said shaft and said circular plate, partition walls mounted on said casing 35 and projecting between said plates to form compartments with said plates, apertures in said circular and said frusto-conical plates, the apertures in said frusto-conical plate being in staggered relationship to the apertures in said circular plate, and means for revolving said shaft, said 40 means comprising a handle keyed to said shaft, and a second means cooperating with said handle for indicating and holding said shaft in such a position that the apertures in said plates are in 45 exact registry with a compartment.

11. A dispenser cap comprising an annular casing having a dispensing port, an annular opening in said casing of substantially the same circumference as the circumference of the mouth of a 55 paper bag, an annular groove surrounding said annular opening and a ring positionable within said groove so that the mouth of the bag may be placed over the opening and the ring placed over the bag to force it into the groove and form an 60 air tight joint, and a frame for holding the bag distended attached to the ring.

12. A dispenser cap comprising a plurality of compartments having a given appreciable depth, an upper and lower closure for said compartments comprising circular plates revolvable together by a common means, two openings in each plate on opposite sides thereof, the openings in said lower plate being on a line at right angles to the line of the openings on said upper plate, 65 means coacting with said plate revolving means to position said plates so that the openings are all in perfect registry with compartments.

JAMES C. BOYLE.
